UNITED STATES PATENT OFFICE.

JACOB A. SUDDERTH, OF BUFORD, GEORGIA.

WASHBOARD.

1,272,142.

Specification of Letters Patent.

Patented July 9, 1918.

Application filed September 20, 1917. Serial No. 192,356.

To all whom it may concern:

Be it known that I, JACOB A. SUDDERTH, a citizen of the United States, residing at Buford, in the county of Gwinnett and 5 State of Georgia, have invented certain new and useful Improvements in Washboards, of which the following is a specification.

The present invention has reference generally to that class of inventions known as 10 laundry and more particularly relates to a wash board.

It is the principal aim and object of this invention to provide a device of the above nature wherein the frame is designed to effectively receive and support brushing 15 means and a rubbing surface either of which is capable of being used to advantage during a washing operation in assuring the cleansing of clothes.

20 As an additional object this invention contemplates the provision of a wash board wherein the brushing means is constructed so as to retain the corrugated rubbing plate in a substantially rigid position in the frame 25 and at the same time serves to brace the brushing means while the clothes are being moved or rubbed thereover.

Among the other aims and object of this 30 invention may be recited the provision of a device of the character described with a view to compactness, and in which the number of parts are few, the construction simple, the cost of production low and the efficiency high.

35 Other improvements and novel details in the construction and arrangement of the various parts of the apparatus will be brought out more in detail in the description to follow, which for a clear understanding 40 of the invention should be considered in connection with the accompanying drawings forming a part hereof, and wherein is disclosed for the purpose of illustration a convenient and satisfactory embodiment of the 45 invention. It is to be noted in this connection that minor changes in the construction and arrangement of parts may be made without departing from the principle of operation of the various parts.

50 The invention is clearly illustrated in the accompanying drawing, in which:

Figure 1 is an elevation looking toward the front face of the improved wash board;

Fig. 2 is an elevation looking toward the other face of the device;

55

Fig. 3 is a vertical section taken on line 3—3, Fig. 1;

Fig. 4 is a vertical section taken on line 4—4, Fig. 1;

Fig. 5 is a fragmentary horizontal, transverse section taken on line 5—5, Fig. 3.

Fig. 6 is a fragmentary top plan of the lower bar of the frame; and

Fig. 7 is a fragmentary plan of the upper bar of the frame.

65

Similar characters of reference are employed in all of the above described views, to indicate corresponding parts.

Referring now, more particularly to the accompanying drawings, there is provided 70 a wash board consisting of a frame embodying the head piece 1 having dove-tailed

grooves in the under surface thereof adjacent the respective ends for engagement with the correspondingly shaped upper 75

ends of side rails 2. These side rails are provided on their inner surfaces with opposed vertical grooves 3 which terminate short of the lower ends thereof. A soap supporting board 5 is arranged transversely of the rails and has its respective 80

ends mounted in the opposed grooves 3 while the upper edge of the board is tenoned in the under surface of the head piece 1. An upper cross bar 6 is now employed, the 85

respective ends thereof being reduced as at 7, and anchored in the side rails just beneath the soap supporting board 5. This cross bar is provided on its upper surface with a longitudinally extending groove 8 90

positioned between the side edges and designed to accommodate the lower edge of the soap supporting board so as to coöperate with the side rails and the head piece in forming soap receptacles on opposite surfaces of the board as is apparent. The under surface of this cross bar is also provided with a longitudinal groove 9 one edge thereof being straight as at 10 while the opposite edge is corrugated or serrated as at 11 forming 95

in effect a cleat or arcuated recess for a purpose that will presently appear.

100

With a view toward providing the co-operating brushing means and rubbing surfaces, the transversely corrugated rubbing plate 12 is provided and has its respective 5 side edges arranged in the lower portions of the opposed vertical grooves 3 in the rails 2 while the upper edge is also flattened and engaged in the groove 9 adjacent the straight edge 10 thereof.

- 10 The improved brushing means consists of a plurality of bars 13 which are semi-circular in cross section and from the arcuate surface 14 of which project transverse series and longitudinal series of brush bristles 15.
- 15 The upper ends of these bars are inserted in the grooves, so that the arcuate surfaces 14 will contact with the corrugated or serrated surfaces 11 of the grooves, while the straight surfaces engage the flattened upper portion 20 of the corrugated plate 12 and serve to clamp the said plate in the groove 9. In removably securing the lower ends of the bars 13 and the lower edge of the plate 12 in position in the frame a lower transverse cross bar 16 is employed. The respective ends of this bar are reduced as at 17 while the upper edge is provided with a longitudinal groove 18. One side of this groove is higher than the other and is corrugated as at 19 for accommodating the lower ends of the bars 13 while the opposite edge is straight for receiving the lower flattened portion of the plate 12 which is also engaged against the flattened surfaces of bars 13 and retained 30 by the latter in a substantially rigid position in the groove. In allowing water to drain through the lower cross bar 16 a series of vertical drainage openings 20 are formed through the cross bar. Likewise in 40 allowing water to drain from the soap receptacle the plate 5 is provided with a horizontal series of spaced openings adjacent the upper cross bar 6 as indicated.

The mode of operation of the present invention may be reviewed as follows: Assuming that the parts have been assembled in the manner described and as indicated in the drawings it is to be appreciated that the rubbing plate 12 may be conveniently 45 used in the customary manner by rubbing clothes thereover and during this operation the brush bars act as struts or braces for preventing sagging of the corrugated plate and in addition co-operate with the upper 50 and lower cross bars in assuring the retention of the said plate in position in the frame. When the brushing means is used it is to be apparent that the corrugated plate 12 serves in a like capacity, that of 55 bracing the bars 13. It is to be appreciated that in the event of breakage of any one of the brush bars the same can be readily replaced with little trouble and slight expense.

The fact that the bristles radiate from the bars 13 and the fact that the bars are arranged in substantially close relation with each other it will also be appreciated that the bristles cover practically the entire surface so that the clothes will at all times be engaged thereby when rubbed thereover.

As many changes could be made in the above construction and many apparently widely different embodiments of this invention could be made without departing from the scope thereof, and it is intended 75 that all matter contained in the above description or shown in the accompanying drawings shall be interpreted as illustrative and not in a limited sense. It is also to be understood that the language used in the 80 following claims is intended to cover all the generic and specific features of the invention herein described and all statements of the scope of the invention which, as a matter of language, might be said to fall therebetween.

Having thus fully described this invention, what is claimed as new and desired to be secured by Letters Patent, is:

1. A device of the character described including a frame embodying side rails, upper and lower cross bars, the adjacent faces of the rails being provided with vertical grooves while the adjacent faces of the cross bars are provided with longitudinal grooves, 95 one edge of each of the longitudinal grooves being straight and the other being serrated, a transversely corrugated rubbing plate having its side edges arranged in the vertical grooves and its upper and lower portions 100 flattened and arranged against the straight edges of the longitudinal grooves, and brush means embodying a plurality of bars arcuate in cross section and a plurality of bristles projecting from the arcuate surface of the bars, the flattened surfaces of the bars being arranged against the flattened portion of the corrugated plate when the arcuate surfaces are engaged against the serrated edges of the longitudinal grooves so that the bars 110 serve to clamp the plate in position, and brace the plate while the plate in addition serves to brace the bars.

2. A wash board including a frame consisting of a head piece, side rails connected thereto, a soap supporting board arranged between the side rails and the head piece, an upper cross bar connected between the side rails for retaining the soap board and cooperating therewith to form soap receptacles, 120 the under surface of the upper cross bar being provided with a groove one edge of which is serrated, the side rails being also provided with opposed vertical grooves, a transversely corrugated rubbing plate arranged in the 125 vertical grooves and in the groove in the up-

per cross bar, brushing means embodying a plurality of bars, bristles extending from the bars, the upper ends of the bars being inserted in the grooves so as to engage the 5 serrated edge thereof and clamp the upper portion of the rubbing plate within the groove, and another cross bar rigidly arranged between the side rails and provided with a groove for accommodating the brush bars and a lower portion of the plate. ¹⁰

In testimony whereof I affix my signature in the presence of two witnesses.

JACOB A. SUDDERTH.
